UNITED STATES PATENT OFFICE.

EDWARD L. HILDERBRAND, OF SULLIVAN, INDIANA.

DESIGN FOR A SPOKE-SOCKET.

SPECIFICATION forming part of Design No. 28,294, dated February 15, 1898.

Application filed January 3, 1898. Serial No. 665,500. Term of patent 14 years.

To all whom it may concern:

Be it known that I, EDWARD L. HILDERBRAND, a citizen of the United States, residing at Sullivan, in the county of Sullivan and State of Indiana, have invented a new and original Design for a Spoke-Socket, of which the following is a specification.

The leading or material features of my design consist of a cylindrical thimble, parallel ears arranged at opposite sides of the thimble and having rounded outer edges, and foot-flanges which flare outwardly from the surface of the thimble and project in opposite directions from the thimble and beyond the edges of the parallel ears.

In the accompanying drawings, Figure 1 is a perspective view of a spoke-socket showing my design. Fig. 2 is a plan view thereof. Fig. 3 is a vertical cross-sectional view.

As shown in the accompanying drawings, my design for a spoke-socket consists of a cylindrical thimble 5, a pair of parallel ears 6 7, and the foot-flanges 8 9. The ears 6 7 lie on opposite sides of the thimble and out of the vertical plane thereof, and these ears

have curved marginal edges 10. The exposed faces of the depending parallel ears 6 7 are curved transversely and they join with the flat inner faces of the ears, forming sharp edges at the side and bottom edges of the ears. The foot-flanges 8 flare outwardly on curved lines from the surface of the thimble, and with these marginal edges of the foot-flanges intersect the curved edges of the parallel ears. Looking at the socket in plan view the foot-flanges present elliptical marginal edges, and a concave surface is between the thimble and the parallel ears, such concave surface being continuous with the concavity of the foot-flanges.

What I claim is—

The design for a spoke-socket herein shown and described.

In testimony that I claim the foregoing as my own I have hereto affixed my signature in the presence of two witnesses.

EDWARD L. HILDERBRAND.
